UNITED STATES PATENT OFFICE.

HERMAN C. STIFEL, OF ST. LOUIS, MISSOURI.

MACHINE FOR GRINDING SHEAVES, &c.

SPECIFICATION forming part of Letters Patent No. 409,254, dated August 20, 1889.

Application filed November 27, 1888. Serial No. 292,010. (No model.)

To all whom it may concern:

Be it known that I, HERMAN C. STIFEL, of St. Louis, Missouri, have made a new and useful Improvement in Machines for Grinding 5 Sheaves and Analogous Articles, of which the following is a full, clear, and exact description.

Considered generally, the improved mechanism is constructed and operated substantially as follows:

10 The sheaves to be ground are delivered into a hopper at the upper end of the machine. From the hopper the sheaves are fed successively downward into a chute. As each sheave arrives at the lower end of the chute, it is 15 clamped laterally and subjected to the action of the grinding mechanism, which is designed to act upon the peripheral portion of the sheave, and to enable the entire peripheral portion to be presented to the grinding mechanism. The sheave and its clamp are rotated 20 during the grinding. After the sheaves are ground they are discharged from the machine, and as a finished sheave is discharged an unfinished one takes its place, to be acted upon 25 by the grinding mechanism.

The capacity of the machine is increased by employing a series of grinding apparatuses in the place of a single one, all substantially as is hereinafter set forth and claimed, aided 30 by the annexed drawings, making part of this specification, in which—

Figure 1 is an elevation of the improved machine, portions thereof being broken away and not shown to enable the remaining portions to be more readily understood; Fig. 2, a plan of the machine; Fig. 3, a central vertical section of the principal portion of the frame-work of the machine; Fig. 4, a horizontal section on the line 44 of Fig. 3; Fig. 5, 35 a vertical section of one of the chutes and grinding mechanisms, the view including the adjacent parts; Fig. 6, a vertical section on the line 66 of Fig. 5; Fig. 7, an edge elevation of the upper portion of one of the chutes; Fig. 40 8, a side elevation of the chute, a portion of the wall being broken away; Fig. 9, a vertical section on the line 99 of Fig. 5; Fig. 10, a side elevation of one of the wheel-supporting arms of one of the grinding mechanisms; Fig. 45 11, a side elevation of the other wheel-supporting arm; Fig. 12, an elevation of one of the brackets used to support the sheave-

clamping mechanisms; Fig. 13, a section on the line 1315 of Fig. 9; Fig. 14, a plan of the bracket-chain in Fig. 12; Fig. 15, a section on the line 1315 of Fig. 9, showing the parts in a different position from that of Fig. 13; Fig. 16, a vertical section showing the parts immediately used in operating the rock-shaft that is employed in opening the grinding-wheel arms apart; Fig. 17, a plan of the box which receives the inner end of the arm used in operating the movable part of the sheave-clamping mechanism; Fig. 18, a view in perspective of the cam used in moving in an outward direction the box of Fig. 17; Fig. 19, a front elevation of the parts of Figs. 17 and 18 shown together; Fig. 20, a side elevation of the bracket for the hand-wheel used in adjusting the grinding-wheel arms when the wheels are worn; Fig. 21, a front elevation of the same; Fig. 22, a side elevation of the hand-wheel and worm-shaft used in the bracket of Figs. 20 and 21; Fig. 23, an end elevation of the same; Fig. 24, a vertical section 75 of the hopper at one of the chutes; Fig. 25, a side elevation of a pair of grinding-wheels and showing a sheave in position for being ground; Fig. 26, an elevation of the mechanism for driving the various mechanisms of the machine; Fig. 27, a vertical section on the line 2727 of Fig. 26.

The views are upon various scales.

The same letters of reference denote the same parts.

The hopper.—At the upper part of the machine is the hopper A, Figs. 1, 3, 5, and 24, for receiving the sheaves to be ground. Its bottom *a* is crowned to facilitate the delivery of the sheaves B, Figs. 3, 5, 8, and 25, into the chutes C, Figs. 1, 3, 4, 5, 7, and 8, and to insure the transfer of the sheaves a stirring device D, Figs. 2, 3, and 5, is employed. This device consists, essentially, of a series of fingers *d d d*, &c., attached to a frame, by means of which the fingers are moved around within the hopper and in contact with the sheaves therein, and so as to urge them in the direction of the chutes. A desirable frame is that shown in the drawings. The fingers at different distances respectively from the wheel-center are attached respectively to the spokes *d'* of a wheel arranged horizontally above the hopper and to turn on a bearing *d''* upon the upper end of

the vertical shaft E; and at its periphery provided with teeth d^3 , to enable it to engage with and be driven by a pinion D', which is fast upon an upright shaft F.

- 5 *The chutes.*—A series of chutes are preferably employed. In the present instance there are twelve chutes arranged to form a circular series extending around the machine. They are shaped in cross-section to receive and to 10 guide the sheaves in an upright position, Figs. 5 and 8, downward, and to deliver them successively to the clamping mechanism, Figs. 1 and 5, belonging to the chute, for with each 15 chute is a complete mechanism for holding the sheaves and grinding them and then discharging them from the machine.

The clamping mechanism is the means for holding and rotating the sheave as it is being ground. To this end the sheave is 20 clamped sidewise and so as to expose its peripheral portion, and as follows: G represents a shaft journaled in bearings g^9 , provided at its inner end with a bevel-pinion g' , and at its outer end g^2 adapted to form a shoulder 25 against which the sheave can be pressed laterally when it has dropped to the lower end of the chute. G' represents another shaft journaled at g^3 in the bracket g^4 , and having its inner end projecting through an opening 30 g^5 , Figs. 5 and 8, in the lower end of the chute, and at its extreme inner end g^6 shaped to enter the central opening b in the sheave and be pressed snugly thereinto. In Fig. 5 the shaft G' is shown pressed endwise against the 35 sheave, and the sheave thereby pressed against the shaft G. When the sheave is thus held, it is caused to rotate with the shafts G G'. The shaft G is driven by means of the horizontal bevel-gear H, Figs. 1, 3, 4, and 5, and 40 while the sheave can be rotated to some extent when the shaft G only is driven, and the shaft G' is used only as a means for producing lateral pressure upon the sheave, it is better to have both of the shafts G G' driven, and 45 driven uniformly. Accordingly the shaft G is provided with a gear g^7 , which engages with and drives a gear g^8 upon a shaft g^9 , Fig. 1. This last-named shaft is held and adapted to be rotated in bearings g^{10} , Fig. 4, and at its 50 outer end provided with a gear g^{11} , which engages with a gear g^{12} upon the shaft G'. By reason of this construction the shaft G' is caused to follow the shaft G in its rotation. When it is desired to release the sheave, the 55 shaft G' is moved endwise away from the shaft sufficiently for the inner end of shaft G' to clear the sheave, whereupon the sheave can drop out of the clamp. The means adapted for thus moving the shaft G' are as follows: 60 The gear H is provided with a cam h, Figs. 5, 18, and 19, which as the gear H rotates encounters a roller h' , Figs. 1, 5, and 19, upon a stud h^2 , which is held in a box h^3 , and thereby moves the box outwardly in the machine. The box 65 is secured to the inner end of the shaft g^9 , and also to the inner end of an arm g^{13} , which passes outward through bearings g^{14} , g^{15} , and

at its outer end supports the bracket g^4 . The parts g^9 and g^{14} are moved outwardly with the box h^3 , and the sheave thereby released. 70 As soon as the cam h passes the roller h' the spring g^{15} , Figs. 1 and 5, which at its inner end g^{16} is secured to the frame of the machine and at its outer end g^{17} to the box h^3 , acts to draw the box h^3 and the parts g^9 , g^{13} inwardly 75 into their original position and to effect the clamping of the next sheave.

The grinding mechanism.—The parts constituting the grinding mechanism are shown in Figs. 1, 2, 4, 9, 10, 11, 13, 15, and 25. The 80 parts which do the actual grinding are the emery-wheels I and I'. The wheel I' is used for grinding the concave portion of the face of the sheaves and the wheel I for grinding the sheave-face at each side of the groove. To 85 enable the wheels to be closed against the sheave when it is desired to grind it and to be opened away from the sheave when it is desired to release the sheave, the wheels are respectively journaled in the arms I^2 , I^3 at the 90 lower end i thereof and the arms in turn, and at the upper end i' thereof are journaled side by side upon a bearing i^2 , arranged toward the upper part of the machine. By swinging the arms I^2 , I^3 upon their bearing the wheels I, I' 95 can be adjusted for the purposes mentioned. The arms are closed toward each other by means of the spring i^3 , Fig. 9, which serves to elastically unite the arms, and to open the arms apart the cam i^4 , Fig. 9, is employed. The 100 cam is fastened upon the rock-shaft i^5 , Figs. 9, 1, 5, and 16, by oscillating which the cam can be turned to open the arms I^2 , I^3 apart and allow them to close toward each other. The rock-shaft is journaled in suitable bearings i^6 , 105 Figs. 1, 5, and 16, and it is operated as follows: The rock-shaft is provided with a crank i^7 . A connecting-rod i^8 leads from the crank i^7 to a bell-crank lever i^9 , which is at i^{10} pivoted to a bearing i^{11} and is provided with a roller i^{12} . 110 As the gear H rotates, a cam h^4 , Figs. 1, 5, and 16, upon it encounters the roller i^{12} and causes the bell-crank to turn on its pivot i^{10} , and the rock-shaft and cam i^4 thereby to turn and effect the opening apart of the arms I^2 , I^3 . As 115 soon as the cam h^4 passes the bell-crank i^9 , the spring i^3 acts, as described, to close the arms I^2 , I^3 toward each other. The movements of the grinding mechanism and the movements 120 of the clamping mechanism, above described, are suitably synchronized.

The chute-closing mechanism.—As the sheaves successively drop into position to be clamped and ground, provision is made for arresting and holding them at the proper level 125 until firmly stamped and ground. For this purpose a gate J, Figs. 1 and 5, is employed. The gate is hung on the shaft G and is movable longitudinally thereon to enable its arm j to close the chute, as represented in Fig. 5, and to be withdrawn to open the chute. A cam j' , upon the gear H, encounters in the 130 rotation of the gear a thrust-bolt j^2 , which works through a bearing j^3 and is fast-

ened to the arm j^4 of the gate and causes the gate to be closed. After the cam j' passes the thrust-bolt the spring j^5 , which leads from the gate-arm j^4 to a bearing j^6 , acts to 5 open the gate. As the lowest sheave in the chute is discharged therefrom, it is desirable to prevent the succeeding sheaves from dropping into the chute until the gate is again about to close. Accordingly a pin K, Fig. 5, is 10 operated to move outward in the bearings k and encounter and bind that sheave which is next to the sheave being discharged when the gate is opened.

The pin K is preferably operated, as described, in the following manner: Arms K' K', Figs. 5 and 6, which are pivoted at K' to a fixed bearing, are jointed at the lower end to the gate J and at the upper end to links k^3 k^3 , Fig. 6, which in turn are jointed to a block 20 k^4 , attached to the pin K. Then when the gate is withdrawn to open the chute the arms k' are turned on their pivot and the pin K is thereby moved outward to bind the sheave.

The grinding-wheel adjustment.—As the 25 wheels I I' wear away, provision is made for adjusting the wheel-arms I² I³ to compensate for the wear. The cam I⁴ upon the rock-shaft i^5 , instead of acting directly upon the arms I² I³, is adapted to encounter an adjustable 30 shoulder L, Figs. 1 and 9, upon the arms I² I³. There being two arms I² and I³, the cam I⁴ is a two-part one, as shown, and the parts are adapted to respectively act upon the arms I² and I³, and each arm is provided with a 35 shoulder L. The shoulder is adapted to be moved in a groove l in the arm toward and from the rock-shaft and to be held at any desired point of adjustment.

The means shown for shipping the shoulder 40 L are as follows: A shaft l', Figs. 1, 9, 22, and 23, journaled in a bearing l², is provided with a worm l³, which engages with a gear-nut l⁴ upon a screw l⁵, which is attached to the shoulder L. By rotating the shaft l' the 45 shoulder is adjusted upon the arm I². That one of the grinding-wheels which is used to grind the sheave-face at the sides of the groove therein must have a lateral play, in order that the wheel-face shall wear evenly. 50 To this end the wheel I is not attached directly to its shaft i²⁰, Figs. 13 and 15, but to a sleeve i²¹, which is feathered on the shaft, to be moved longitudinally upon and to rotate with the shaft, and is provided with a cam-groove i²², Figs. 13 and 15, in which a clutch-lever i²³, Fig. 9, engages. Then as the wheel-shaft i²⁰ rotates, the clutch-lever, by mechanism not shown, operates to shift the sleeve reciprocatingly upon the shaft i²⁰, and thereby 55 to shift the wheel I to and fro, as indicated by its two positions, shown respectively in Figs. 13 and 15.

The driving mechanism.—Power is communicated to the machine by means of the 60 pulley M, Figs. 26 and 27, which is fast upon the shaft m, which in turn is provided with

the bevel-gear m' and the cone-pulley m², by which means the rotation of the shaft m is transmitted in two different directions. The gear m' drives a bevel-gear f upon the upright shaft F, Figs. 26, 27, 1, and 2, upon whose upper end is the pinion D', which drives the gear D. The cone-pulley m², by means of a belt m³, communicates its motion to a cone-pulley m⁴, Fig. 1, which is fast upon a horizontal shaft m⁵. This last-named shaft is provided with a bevel-pinion m⁶, which drives a bevel-pinion O, fast upon the upright shaft E, Figs. 1, 2, 3, and 4. This shaft at its upper end, as stated, provides a bearing for the gear D to be turned thereon, and beneath the hopper A the shaft has fastened to it the bevel-gear P, Figs. 3, 1, and 5. This last-named gear, therefore, rotates with its shaft E and serves, through the bevel-pinion q, to drive the horizontal shaft Q, Figs. 5 and 9. The shaft Q is provided with a pulley q', from which belts q² lead to and around the pulleys q³ q³, Fig. 9, upon the wheel-shafts i²⁰ i¹⁰ respectively. The grinding-wheels are thereby driven from the shaft Q. The belts are respectively carried past idler-pulleys q⁴ q⁴ and around a wheel-shaft pulley q³, as shown. In this manner the grinding mechanism is driven. The mechanism Q q, &c., is duplicated for each 90 grinding mechanism. The upright shaft F is also provided with a bevel-gear f², which drives, through the medium of a bevel-pinion r, Fig. 1, a shaft R, having a worm r', which engages with and drives a horizontal gear r², 100 Figs. 1 and 3. This last-named gear and the gear H, above described, are both fastened upon an upright sleeve S, journaled upon the bearing s, Fig. 3. The gear H thereby is driven from the shaft F, and its motion in turn effects 105 the rotation of the clamp-shafts G', Figs. 1 and 5, as well as the other various movements above set forth.

I claim—

1. The combination of the hopper, the series 110 of chutes, the shafts E F, the pinion D', and the gear D, having the fingers d d, substantially as described.

2. The combination of the chute, the shafts G' g⁹, the pinion g', the bracket g⁴, the gear 115 H, and the gears g⁷ g⁸ g¹¹ g¹², substantially as described.

3. The combination of the gear H, the cam h, the roller h', the stud h², the box h³, the shaft g⁹, the arm g¹³, the bracket g⁴, and the 120 spring g¹⁵, substantially as described.

4. The combination of the chute, the wheels I I', and the journaled arms I² I³, substantially as described.

5. The combination of the clamping-shafts 125 G G' and the grinding-wheels, one of said shafts being adjustable toward and from the other and both of them being rotatory, and said wheels being held in arms capable of being moved toward and from each other, substantially as described.

6. The combination of the chute, the grind-

ing-wheels and their journaled arms, the spring i^3 , and the cam i^4 and its shaft, substantially as described.

7. The combination of the chute, the grinding-wheels and their journaled arms opening apart from and closing toward each other, as described, the clamping-shafts, and the chute-gate, one of said shafts being adjustable toward and from the other, and both of the shafts being rotatory, and said gate being made to close and open said chute, substantially as described.

8. The combination of the gear H, the cam h^4 , the roller i^{12} , the bell-crank i^9 , the journaled arms $I^2 I^3$, the rock-shaft i^5 , the cam i^4 , the spring i^3 , the crank i^7 , and the rod i^8 , substantially as described.

9. The combination of the gear H, the cam h^4 , the thrust-bolt j^2 , the spring j^5 , the gate J, and the chute, substantially as described.

10. The combination of the grinding-wheels and their arms, the adjustable shoulders L, and the rock-shaft and cam i^4 , and spring i^3 , substantially as described.

11. The combination of the arm I^2 , the adjustable shoulder L, the shaft l' , the worm l^3 , the nut l^4 , and the screw l^5 , substantially as described.

12. The combination of the grinding-wheels and the arms $I^2 I^3$, one of said wheels being adjustable laterally to enable it to wear evenly, substantially as described.

13. The combination of the shaft E, the gears P q , the shaft Q, the pulley $q' q^3 q^3$, the belts q^3 , and the arms $I^2 I^3$, substantially as described.

14. The combination of the shafts R F, the gear $r^2 f^2 H$, the pinion r , the worm r' , and the sleeve S, and its bearing, substantially as described.

Witness my hand this 3d day of November, 40
A. D. 1888.

HERMAN C. STIFEL.
